(57) **CLAIM**

The ornamental design for a solar module, as shown and described.

DESCRIPTION

FIG. 1 is a top perspective view of a solar module according to our new design;

FIG. 2 is a top view thereof;

FIG. 3 is a bottom view thereof;

FIG. 4 is a front view thereof;

FIG. 5 is a rear view thereof;

FIG. 6 is a right-side view thereof; and,

FIG. 7 is a left-side view thereof.

The broken line showing is included for the purpose of illustrating features and environment and forms no part of the claimed design.

The dot-dash broken lines show the boundary of the claimed design.

1 Claim, 7 Drawing Sheets
